UNITED STATES PATENT OFFICE

HERMAN CAREW, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA

PAPER CUP

Application filed August 22, 1930. Serial No. 477,099.

My invention relates to new and useful improvements in receptacles and more particularly to paper cups or the like intended for but a single use and adapted to be nested 5 in stack formation so that the terminal cup may be withdrawn for use.

The principal object of the invention resides in the provision of a receptacle of the character described which is relatively simple and inexpensive in construction, being formed of relatively light material, and of a construction adapting a relatively large number to be nested in a relatively small stack thereby facilitating their use in dispensing 15 machines and making it unnecessary for the attendant to frequently refill or replenish the dispensers.

Another object consists in providing a receptacle of the character described having 20 advantages of both the cylindrical and flat types previously used, the same being provided with a round normally open mouth portion and a body portion which is of substantially wedge-shape tapering downwardly 25 to provide a flat relatively wide bottom adapted to be engaged by the fingers when removing the terminal receptacle from a stack or while using.

A further object of the invention resides 30 in the formation of a receptacle or cup, of the character described, from but two blanks or pieces of material, the blanks or pieces of material being folded and secured together to provide the completed receptacle or cup.

A still further object of the invention consists in providing a cup of the character described which is formed in such a manner as to prevent leakage while in use.

With the above and other objects in view, 40 which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended 45 claims.

In the drawings:—

Fig. 1 is a side elevation.

Fig. 2 is a vertical section on the line 2—2 of Fig. 1.

Fig. 3 is a top plan.

Fig. 4 is a horizontal section on the line 4—4 of Fig. 1.

Fig. 5 is a section on the line 5—5 of Fig. 1.

Fig. 6 is a horizontal section on the line 6—6 of Fig. 1.

Figs. 7 and 8 are plan views of the two blanks from which the receptacle is formed.

Fig. 9 is a perspective showing the manner in which the blank disclosed in Fig. 7 is folded; and

Fig. 10 is a perspective showing the manner in which the blank disclosed in Fig. 8 is folded to be attached to the folded blank shown in Fig. 9.

The receptacle or cup is formed from the 70 paper blanks *a* and *b* illustrated more particularly in Figs. 7 and 8 of the drawings. The blank *a* is of sector shape including the arcuate top edge 1, the inwardly converging side edges 2 and 3, and recessed bottom 75 formed by continuing the side edges downwardly below the horizontal edge 4 to provide the substantially V-shaped projections 5 and 6, the inner edges of the projections shown at 7 and 8 extending at an angle relative to the horizontal edge 4. The blank *b*, shown in Fig. 8, is of elongated shape forming the parallel top and bottom edges 9 and 10 and the parallel side edges 11 and 12.

To form the receptacle or cup the blank or 80 strip of material shown in Fig. 7 is folded as shown more particularly in Fig. 9 of the drawings and when so folded the edges 7 and 8 of the projections 5 and 6 extend parallel with the horizontal edge 4 and the side edges 85 2 and 3 extend vertically with a space therebetween. The strip *b* shown more particularly in Fig. 8 of the drawings is adapted to be secured to the folded blank shown in Fig. 9 and to form the closed bottom of the receptacle. To secure the blank *b* to the folded blank *a* the top edge 9 is bent downwardly on the line 13 and the bottom edge 10 is folded upwardly on the line 14, the folds of the top 90 and bottom edges being quite clearly illus- 100

trated in Fig. 10 of the drawings. The folded top and bottom edges are positioned over the same face of the blank and when the blank *b* is secured to the folded blank *a* the upwardly turned bottom edge of the blank *b* will extend beneath the bottom edges of the folded blank *a* and form a closure for the bottom of the receptacle or cup. The downwardly turned top edge of the blank *b* will engage over the top edge of the folded blank *a*, on opposite sides of the space formed by the spaced edges 2 and 3. It will be understood that the blank *b* forms a closure for the space between the vertically extending edges 2 and 3 and when secured to the folded blank *b* forms a complete cup or receptacle of substantially wedge-shape with a normally open circular mouth portion.

It will be understood that for securing the blank *b* to the folded blank *a* that a suitable adhesive may be applied along the edges of the small blank *b* or along the edges of the blank *a*. The edges of the blank *b* overlie the substantially vertical edges 2 and 3 of the folded blank *a* a sufficient distance as to provide a tight closure along the edges and the upwardly turned bottom edge of the blank *b* is of sufficient width to extend completely beneath the bottom edges of the folded blank *a* so that there can be no leakage at the bottom of the receptacle or cup.

From the above detail description it is thought that the construction of my cup or receptacle will be clearly understood. By having the receptacle or cup of substantially wedge-shape I secure the advantages of the ordinary flat type of cup for nesting purposes and by having the normally opened mouth portion I secure the advantages of the ordinary cylindrical form of receptacle or cup. The receptacle or cup is also of such a formation that a relatively wide flat bottom edge is provided to be grasped when removing a terminal cup or receptacle from a stack and while using. In view of the fact that the receptacle or cup is formed of the two pieces of material, and in view of the fact that the material may be relatively thin, the receptacles or cups may be inexpensively made. The two parts or blanks going forward to make up the completed receptacle or cup are secured together, in the manner described, to prevent any leakage of material while the receptacle or cup is being used.

Having fully described my invention what I claim as new and desire to secure by Letters Patent is:

1. A receptacle formed from connected pieces of material, one piece being shaped to form a tapered body with an open face and the other piece being secured over the open face to hold the body in its tapered form and having a portion folded to provide a closure for the bottom of the receptacle.

2. A receptacle formed from connected

pieces of material, one piece being shaped to form a tapered body with an open face and the other piece being secured over the open face to hold the body in its tapered form and having its lower end folded beneath the body and secured to the opposite face thereof to form a closure for the bottom of the receptacle. 70

3. A receptacle formed from connected pieces of material, one piece being shaped to form a body with an open face and the other piece being secured over the open face with its upper end folded over the top edge of the body and its lower end folded beneath the bottom edges of the body to form a closure 80 therefor. 75

4. A receptacle formed from connected pieces of material, one piece being shaped to form a body with spaced parallel edges forming an open face, and the other piece overlying the parallel edges and secured thereto, the lower end of the second mentioned piece being folded beneath the bottom edges of the body to form a closure therefor, and the upper end being folded over the top edge of the 90 body and secured thereto. 85

5. A receptacle formed from connected pieces of material, one piece being shaped to form a wedge-shaped body with a normally open mouth portion, a relatively flat bottom portion, and an open vertical face, and the other piece being secured over the open vertical face with its lower end folded beneath the relatively flat bottom portion of the body to form a closure therefor. 95

6. A receptacle formed from connected pieces of material, one piece having an upper arc, radial sides and a recessed bottom edge, whereas the other piece is of elongated shape, the first mentioned piece being shaped to form a body with a normally open mouth portion, a relatively flat bottom portion and an open vertical face, and the second mentioned piece being secured over the open vertical face with its lower end folded beneath 110 the substantially flat bottom of the body to form a closure therefor. 100

7. A receptacle formed from connected pieces of material, one piece having an upper arc, radial sides and a recessed bottom edge, whereas the other piece is of elongated shape, the first mentioned piece being shaped to form a body with a normally open mouth portion, a relatively flat bottom portion and an open vertical face, and the second mentioned piece being secured over the open vertical face with its lower end folded beneath the substantially flat bottom of the body to form a closure therefor and its upper end being folded over the upper edge of the body. 115 120

In testimony whereof I hereunto affix my signature.

HERMAN CAREW.
